(57) CLAIM

The ornamental design for a car chalking box, as shown and described.

DESCRIPTION

FIG. 1 is a side elevational view of the car chalking box showing in dotted lines the chalking line extending therefrom, wherein the opposite side is a mirror image of that shown in FIG. 1.

FIG. 2 is a top plan view of the car chalking box.

FIG. 3 is a bottom plan view of the car chalking box.

FIG. 4 is a front elevational view of a car chalking box; and,

FIG. 5 is a rear elevational view of the car chalking box. The broken line showing is for illustrative purposes only and forms no part of the claimed design.
